UNITED STATES PATENT OFFICE.

CHARLES H. NORTON, OF WORCESTER, MASSACHUSETTS, ASSIGNOR TO NORTON COMPANY, OF WORCESTER, MASSACHUSETTS, A CORPORATION OF MASSACHUSETTS.

GRINDING MACHINE FOR FORMING ROLLS.

Application filed January 5, 1921. Serial No. 425,098.

To all whom it may concern:

Be it known that I, CHARLES H. NORTON, a citizen of the United States of America, residing at Worcester, in the county of

5 Worcester and State of Massachusetts, have invented certain new and useful Improvements in Grinding Machines for Forming Rolls, of which the following is a full, clear, and exact specification.

10 My invention relates to cylindrical grinding machines of the type shown, for example in my Patent No. 762,538, dated June 14, 1904, and more particularly to a roll forming attachment for such machines.

15 Forming attachments have heretofore been used in connection with the relatively movable work tables of cylindrical grinding machines which caused one table to move transversely of the other while they were

20 traversed past the grinding wheel, thereby giving the work the desired form. In some instances it has been proposed to swivel the work-carrying table on the longitudinally sliding table adjacent one end thereof and

25 to provide a finger adjacent the opposite end of the swivel table, this finger bearing against a templet or forming bar supported on brackets on the base of the machine. Such a device is, however, unsuited for pro-

30 ducing accurate work, where the work has to be ground to within a thousandth of an inch of a given diameter, because of the tendency to push the traversing table transversely off the ways on the base, said ways being usually one flat and the other V-shaped.

It is accordingly a principal object of my invention to overcome such difficulties by providing a grinding machine with a forming attachment in which the forces causing

40 relative movement between the tables act between the tables, thereby eliminating this tendency to push the sliding table off the ways and the consequent inaccuracies in the work. To this end I may employ a longi-

45 tudinally reciprocating table carrying a transversely movable table, said tables bearing cooperating opposed follower members adapted to engage a forming bar fixed as regards longitudinal movement and extending

50 between said members.

It is a minor object of my invention to provide a pivotal connection between the tables which reduces lost motion and friction to a minimum and to provide for the

55 adjustment of said follower members to-

wards each other, whereby the work may be held steady and brought into parallelism with the table ways.

With the foregoing and other objects in view which will become apparent as the description proceeds, the invention consists in the combination and arrangement of parts and in the details of construction herein-after described and claimed, it being understood that changes in the precise embodiment of the invention as herein disclosed may be made without departing from the spirit of the invention.

Referring to the accompanying drawings which are made a part hereof and in which similar reference characters refer to similar parts.

Figure 1 is a front elevation of a grinding machine equipped with my improved forming attachment;

Fig. 2 is a plan view of the work table showing the device applied thereto;

Fig. 3 is an enlarged fragmentary sectional view through the roller carrying brackets, lower table, and base, taken approximately on the line 3-3 of Fig. 4 and showing a table driving mechanism:

Fig. 4 is a fragmentary plan of the parts shown in Fig. 3, excluding the table driving mechanism;

Fig. 5 is an enlarged transverse vertical sectional view through the pivotal connection between the tables;

Fig. 6 is a horizontal section through the pivot, taken approximately on the line 6-6 of Fig. 5, parts of the table being broken away; and

Fig. 7 is a fragmentary sectional detail view showing the manner of mounting of the spring which forces the rollers at the opposite end of the tables into contact with the forming bar.

In the specific embodiment of my invention selected for illustration, I have shown my device applied to a grinding machine of the Norton type, as shown in the patent above referred to, and in which the work table 1 is mounted to slide longitudinally on the usual ways on the base 2 and is provided with the usual means for traversing it either by hand or automatically, as is fully described in said prior patent. In Fig. 3 I have shown only the hand traversing means, which consists of a rack 3 rigidly connected to the under side of the table 1 and driven

from the hand wheel 4 through the gearing 5, shaft 6 and pinion 7, the latter engaging the teeth of the rack. On the table 1 is mounted the transversely movable table 10 which may be of the usual swivel construction except as modified for the purposes of my invention. On the table 10 are mounted the headstock 11 and tailstock 12 which may be of any suitable construction for supporting and rotating the work. Where the work comprises a heavy roll 13 having end bearings 14, I preferably support it in work supports 15 with or without the use of the tailstock and rotate it by having its squared end 16 engage a similarly shaped opening 17 in a driven member 18 on the headstock 11. I have shown the latter as being motor driven in a manner similar to that shown in my Patent No. 1,152,434, dated September 7, 1915. I do not desire to be limited to the specific manner of supporting and rotating the work which is merely illustrative and forms no part of the present invention.

In order to effect a relative transverse movement between the tables 1 and 10 while the work is traversing past the grinding wheel 19 to give the desired form to the work, I provide opposed follower members such as the rollers 20 and 21 between which is supported a forming bar 22 of desired configuration and these rollers are held against the opposite sides of the bar by any suitable means such as the spring 23. In the present instance I have shown my device adapted for crowning rolls and the rollers are arranged adjacent one end of the tables while the table 10 is swivelled on a pin or roll 24. The forming bar may be tapered from end to end so as to produce a paraboloid. It is supported by a block 25 (Figs. 3 and 4) between the rollers and a bracket 26 (Fig. 1) extending upwardly from the base. The bar is pivoted to this bracket to allow swinging movement thereof. To provide for the ready substitution of different bars, I may connect the bar as by screws 28 to a short arm 29 which is in turn pivoted at 27 to the bracket 26.

The rollers are preferably mounted on substantially vertical pivots arranged in opposed relation at the right-hand end of the tables as shown in Figs. 1 and 2. The inner roller 20 is located in a downwardly opening recess 30 formed in a bracket 31 which is preferably removably secured to the end of the swivel table 10 as by screws 32. A headed stud 33 supports the roller and serves as a pivot pin therefor. I have shown this stud securely held as by set screws 34 in a hole in the bracket 31. The outer roller 21 is shown supported in a bracket 35 suitably connected to the table 1. I have shown it formed integrally with the table to provide a rigid construction and to render its manufacture easy. An upwardly opening

recess 36 is provided in this bracket to receive the roller 21 and a hole is provided in the bracket below said recess and opening thereto to receive the lower end of the stud 38 on which the roller is pivoted. The upper end of said stud extends into a hole 39 formed in a top plate 40 closing the recess in the bracket and secured thereto by screws 41.

It is desirable, under certain conditions, as will be pointed out in describing the operation of the device, to effect a slight lateral adjustment of one of the rollers 20 or 21. I have provided a construction in which the axis of the roller 21 is made adjustable and I conveniently accomplish this adjustment by making the part 42 of the stud 38 on which the roller is pivoted eccentric to the end portion, by extending the upper end portion beyond the top plate 40, and forming it with a squared portion 43 for engagement with a suitable tool for rotating it. Rotation of the stud will obviously shift the axis of rotation of the roller 21. I may provide this stud between the squared portion 43 and the top plate 40 with a tapered collar 44 provided with graduations 45 co-operating with a suitable index 46 on the top plate for indicating the amount of lateral movement of the roller axis and consequently of the end of the swivel table. When once adjusted, the stud is locked in place by suitable clamping screws 47.

As a means for moving the tables 1 and 10 relatively to cause the rollers 20 and 21 to bear against the forming bar at all times during the grinding operation, I may employ a stiff helical spring 23 bearing with one end against an upwardly extending bracket 50 on the table 1 and with its other end against the side of the table 10 adjacent one end thereof. The ends of the spring are held in place by suitable studs 51 and 52 secured to the tables 1 and 10 respectively. To allow of adjusting the tension of the spring, I provide the stud 51 with a relatively long screw threaded portion 53 engaging a screw threaded hole in the bracket 50 and provide its outwardly extending end with a hexagonal or otherwise shaped head 54 suitable for receiving a wrench to turn it. A clamping screw 55 is provided to lock it in place.

I have discovered that the ordinary pivotal connection consisting of a stud on one table engaging in a hole on the other is unsuitable for accurate work in connection with my work forming device. I therefore utilize a special pivotal connection which minimizes friction and effectually avoids lost motion. This device may consist of opposed bearing blocks having V-shaped recesses 58 and 59, the bearing blocks being arranged respectively on the tables 1 and 10 and receiving between them the hardened roll 24,

as is clearly shown in Figs. 5 and 6. The V-shaped recesses are arranged to face toward the front and the rear of the machine respectively, and there is sufficient clearance 5 between the blocks to allow of the desired amount of pivotal movement between the tables.

In the operation of my machine, supposing that it is desired to grind a roll with a 10 given amount of crown and so that the surface of the roll is curved uniformly from end to end, a templet or forming bar 22 having a straight taper from end to end, as is shown in Fig. 2, is then utilized. The 15 table 1 is first moved to bring one end of the roll, let us say the left-hand end, Figs. 1 and 2, opposite the grinding wheel and the grinding wheel is fed into contact with the roll by the usual feeding mechanism indicated at 61, Fig. 1. If the roll is cylindrical and its axis is parallel with the path of reciprocation or the ways of the table 1 when the grinding wheel is opposite the longitudinal center of the roll, then with the 20 parts in the position first supposed, the left-hand end of the roll is nearer to the grinding wheel axis than the right-hand end. As the table is traversed to the left from this position, the swivel table is swung by the tapered bar until the work axis is parallel to 25 to table ways when the wheel is opposite the center of the roll and from there on the roll axis will incline in the opposite direction to the table ways until the wheel again 30 touches the roll at the right-hand end. The grinding is then continued until the wheel has ground the entire surface of the roll and the roll has reached the desired dimensions. If the roll axis should happen to be 35 slightly out of alignment with the table ways, and this can be determined by caliper- 40 ing the opposite ends of the roll after they have both been ground to some extent, in which case they will be of different diam- 45 eters, it will be necessary to effect some adjustment to bring about correct alignment. This is conveniently accomplished in my de- 50 vice by applying a wrench to the squared portion of the stud on which the roller 21 is eccentrically pivoted and moving the pivot either toward or away from the axis of the roll as may be required to effect the necessary alignment.

By this construction I have provided a 55 very precise and reliable forming attachment for a plain cylindrical grinding machine which can be readily changed to adapt it for grinding cylindrical work of various contours, such as convex, concave, sinuous 60 or straight cylindrical work, as may be desired. It also enables me to readily convert a plain cylindrical grinding machine, such as is shown in my prior patent above referred to, into a machine for grinding 65 formed work by substituting the tables

equipped with my form grinding attachment for the usual tables shown in the patent, and fastening the forming bar in proper position on the base.

Having thus described my invention, what 70 I claim as new and desire to secure by Letters Patent is:

1. A grinding machine comprising a base, a reciprocable table mounted thereon, means for reciprocating said table, a transversely movable table on said reciprocable table, and means including a follower on each of said tables and a forming bar held against longitudinal movement and extending between said followers to move the tables 80 transversely relative to each other as they reciprocate.

2. A grinding machine comprising a base, a reciprocable table mounted thereon, a swivelled table on said reciprocable table, means for reciprocating said tables, opposed followers on said tables respectively, means acting to move one of said followers towards the other, and a longitudinally stationary forming bar extending between said 90 followers for controlling the movement of said tables relative to each other as they reciprocate.

3. A grinding machine comprising a base, a reciprocable table mounted thereon, means for reciprocating said table, a transversely movable table mounted on said reciprocable table, work-supporting means on said transversely movable table, a grinding element 95 adapted for operative engagement with the work, and means including a follower on each of said tables and a forming bar mounted to swing transversely but held against longitudinal movement and extending between said followers to move the upper table 100 transversely as it reciprocates.

4. A grinding machine comprising a base, a table mounted for reciprocation on said base, a second table mounted on said reciprocable table for pivotal movement about a point between its ends, opposed followers on said tables respectively and arranged adjacent one end thereof, a forming bar pivoted on said base to allow transverse movement and extending between said followers, and means adjacent the opposite end of said tables for relatively holding the followers in engagement with the opposite sides of the bar in all operative positions thereof.

5. A grinding machine comprising a base, a reciprocable table mounted thereon, means for reciprocating said table, a second table mounted for transverse movement on said reciprocable table, brackets fastened to said tables at transversely opposite points, rollers mounted on said brackets in substantially the same horizontal plane, resilient means urging one of said rollers towards the other, 125 means for adjusting the tension of said 130

resilient means, and a forming bar extending between said rollers and engaged by said rollers on opposite sides thereof, said forming bar being relatively stationary while the tables reciprocate.

6. A grinding machine comprising a base, a reciprocable table mounted thereon, means for reciprocating said table, a second table mounted on said reciprocable table for pivot-
10 al movement about a point substantially midway of its length, rollers mounted on said tables adjacent one end thereof, a forming bar stationary as regards longitudinal movement and projecting between said rollers, and spring means adjacent the opposite end of said tables for causing the pivoted table to swing about its pivot to hold the rollers against the opposite sides of said bar.
7. A grinding machine comprising a base, a reciprocable table mounted thereon, a transversely movable table on said reciprocating table, a pair of opposed followers on said tables, a forming bar fixed as regards longitudinal movement and extending be-
20
25

tween said followers, means to move said transversely movable table to hold said followers in engagement with opposite sides of the forming bar, and means for adjusting one of said followers in a direction towards 20 or from the other.

8. A grinding machine comprising a base, a longitudinally reciprocating table mounted thereon, a swivelled table on said reciprocating table for supporting the work, a pair 35 of opposed rollers on said tables, a tapered forming bar pivotally mounted on said base and extending between said rollers, and means for relatively holding said rollers against the opposite sides of said bar, one 40 of said rollers having an eccentrically mounted pivot whereby said roller may be adjusted towards or away from the other by rotation of its pivot, and the work axis may be placed in parallelism with the path of 45 reciprocation of the table.

Signed at Worcester, Massachusetts, this
3rd day of Jan., 1921.

CHARLES H. NORTON.
